UNITED STATES PATENT OFFICE.

S. H. LYON, OF NEW YORK, ASSIGNOR TO HIMSELF AND R. T. WILDE, OF BROOKLYN, NEW YORK.

IMPROVEMENT IN APPARATUS FOR FORMING HATS AND BONNETS.

Specification forming part of Letters Patent No. 41,342, dated January 19, 1864.

To all whom it may concern:

Be it known that I, S. H. LYON, of the city, county, and State of New York, have invented certain new and useful Improvements in Machinery for Pressing Hats and Bonnets; and I do hereby declare that the following is a full, clear, and exact description of the same, reference being had to the accompanying drawings, forming part of this specification, in which—

Figure 1 is a front view of the lower part of a hat-pressing machine constructed according to my invention. Fig. 2 is a central vertical section of the machine at right angles to Fig. 1. Fig. 3 is a plan of the same.

Similar letters of reference indicate corresponding parts in the several figures.

This invention relates to the employment of mechanical clamps for the purpose of holding the brim of the hat or the margin of the piece of felt or other fabric of which a hat is formed, and of drawing and stretching the same over the former or hat-block preparatory to and during the operation of the die. Such clamps as heretofore constructed have consisted of a pair of rings or elliptic-shaped frames which have taken hold of the margin of the brim or piece all around, and these could not be used successfully in the manufacture of hats from sheets of felt and some other fabrics, owing to their liability to tear the fabric, and are, moreover, inconvenient on account of their not being adjustable for hats of various sizes. With a view to obviate the above objection the first part of the invention consists in the employment, in combination with the block or former and die of a hat-pressing machine, of a number of separate clamps to take hold of the felt or fabric at its corners, or at suitable intervals, but not all around, thereby leaving the fabric free to be drawn inward or contract from certain points as it is stretched from other points, as herein-after described. Other features of the invention consist in making such clamps adjustable and in certain arrangements of and certain modes of adjusting and operating the clamps or stretching apparatus.

To enable others skilled in the art to make and use my invention, I will proceed to describe its construction and operation.

A is the bed or base of the machine, having erected on it at or near its center the standard B, which supports the hat-block or former C. The die which comes over the block or former to press and form the hat is not shown, but it may be applied and operated in the usual or any suitable manner.

D is a frame, to which the clamps are attached, supported upon two upright bars, E, which are fitted to slide through suitable guides, F, secured to the base A. This frame has its interior considerably larger than the largest part of the exterior of the hat-block or former, upon which the brim of the hat is formed. The lower portions, G, of the clamps are composed of two flat plates of semi-elliptical, semicircular, or other substantially similar form, toothed or roughened, as shown at e, in a suitable manner to enable them to bite the cloth, and these are bolted to the frame D—one in front and the other at the back—by means of bolts b, which, by passing through slots d in the frame, enable the said clamps to be brought nearer together or farther apart to suit larger or smaller hats. The upper portions of the clamps are composed of four separate pieces, H, curved in a manner to conform to the plates G, and toothed or roughened in a similar manner on their under sides. These four pieces H are bolted or otherwise secured to two rock-shafts, J, which are arranged at the sides of the machine in bearings e, secured to the plates G, two of the said levers being secured to each rock-shaft. The bearings of each rock-shaft are attached one to each of the plates G, and the two clamping-pieces H, belonging to each shaft, operate one in connection with one plate G and the other in connection with the other. The levers I are so secured to their respective shafts that they may be unfastened and moved along it for the purpose of enabling the pieces H to be adjusted to the pieces G when the latter are adjusted nearer together or farther apart for smaller or larger hats. In the adjustment of the pieces H the levers I are always brought close to the bearings e, which, being attached to the plates G, form gages to set the pieces H. The lower arms of the two front levers, I—one on each shaft—are extended under the frame D, as shown in Fig. 1, and upon the ex-

tremity of each of the said arms there is pivoted a hand-lever, K, upon which there is formed a cam, f, which, by pulling forward the said lever, is made to act against the bottom of the frame D in such manner as to draw down the lever I, to which it is attached, and so made to bring its clamping-piece H and the corresponding clamping-piece attached to the same shaft into operation, in combination with the clamping-plates G, to grasp the felt or other material of which the hat is composed. When the levers K are thrown back, the front levers, I I, are raised by springs g, connecting them with the frame, and the clamping-pieces H are thereby raised.

The upright sliding bars E are furnished with toothed racks l, gearing with two pinions, L, on a horizontal shaft, M, which works in suitable bearings, k, attached to the standards which contain the guides F. This shaft is furnished in front of the machine with a hand-crank, N, by which to turn it for the purpose of raising and lowering the bars E with the frame D and attached clamps, and is also furnished behind the crank with a ratchet-wheel, P, and a pawl, m, is applied to act upon the said ratchet-wheel for the purpose of retaining the frame D and clamps at any desired height.

The upright bars E are connected with the front and back of the frame D, by means of hinges or pivot-joints n, in such manner as to permit either the front or back of the frame D to be raised or lowered for the purpose of giving the frame any inclination in a backward and forward direction that may be desirable. This inclination is more especially necessary in the making and pressing of bonnets of some forms.

The operations of the clamps are as follows: Before putting the felt or other material of which the hat or bonnet is to be formed into the machine the upper die is raised in the usual manner, the clamps are raised entirely above the block or former C by turning the crank N, and thereby raising the frame D to a suitable height. The frame D is then held up by the pawl m while the fabric is inserted, the clamps being open. The fabric is of square or quadrangular form, as cut from the piece by cutting longitudinally and transversely, and when put in between the clamps and secured by drawing forward the levers K is held at the four corners by the upper portions, H, of the clamps pressing one across each corner, as shown in Fig. 3, where, as in Fig. 2, the fabric is shown in red outline. The single attendant who operates the machine then takes hold of the crank N, and, after throwing out the pawl m from the ratchet wheel P, turns the shaft M in a direction to depress the frame D and the clamps, and by that means the fabric is drawn down over the block or former C, in the manner illustrated in Fig. 2, to a condition to be operated upon by the upper die, which is brought down upon it in

the usual manner and allowed to remain upon it long enough to produce the desired effect, when the said die is raised and the clamps are opened and the hat or bonnet removed from the block or former C. The pawl m is then returned to the ratchet-wheel and the frame D and clamps raised up again, as at first described, to receive a new piece of fabric.

In the above operation the four clamps act like the four hands of the two attendants generally employed in operating a hat-pressing machine—one standing in front and the other at the back of the machine—taking hold of a sufficient portion of the surfaces of the felt or other fabric to avoid tearing it at the corners, but at the same time leaving portions of the sides of the fabric free to contract or be drawn inward, to compensate in some degree for the stretch to which other portions are subject, and thus preventing the tearing of the hat, which sometimes occurs when the upper and lower dies each consist of a continuous piece. The blanks of which the hats are formed are commonly larger from back to front than from side to side, and as felt cloth—the material from which hats are most commonly made in machines of this kind—will only stretch in one direction—viz., crosswise of the piece—the length of the blank is cut in that direction, and, as with my improved system of clamps a greater portion of the longer sides is left out of the clamps, those sides, instead of being required to stretch, are more free than the other sides to be drawn inward, to make up for the necessary stretch lengthwise or cornerwise of the blank in forming the hat.

I will here remark that I have understood that it has been attempted to employ hooks in hat-pressing machines for a purpose similar to my separate clamps, but that such hooks have been liable to the same objection as the continuous clamps—viz., the tearing of the fabric.

I do not claim, broadly, the use of mechanical clamps in machines for forming hats when such clamps are made continuous all round the block or former; nor do I claim the use of hooks in such machines for holding the blank or hat at intervals; but

What I claim as my invention, and desire to secure by Letters Patent, is—

1. The employment in a machine for pressing or forming hats of separate clamps arranged to take hold of the fabric at the corners or at suitable intervals, substantially as and for the purpose herein described.
2. Making such clamps adjustable to suit hats of various sizes, substantially as herein described.
3. The attachment of the upper portions, H, of the clamps to levers I, carried by two rock-shafts, J, and operated by cam-levers K, the whole arranged in connection with the frame D, and operating substantially as herein described.

4. The arrangement of the bearings *e* of the rock-shafts *J* upon the lower clamp-plates, *G*, to serve as gages by which to adjust the upper clamping pieces, *H*, relatively to the said plates *G*, substantially as herein described.

5. Supporting the clamps upon two toothed rack-bars, *E*, or their equivalents, which are so jointed at their upper ends as to permit

either end of the clamps to be raised or lowered at pleasure, substantially as and for the purpose herein described.
